UNITED STATES PATENT OFFICE

HENRY P. PINKHAM, OF WOLLASTON, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS

GAS AND LIQUID SEPARATOR

Application filed September 1, 1927. Serial No. 216,878.

This invention relates to gas and liquid separators and especially to oil separators associated with oil immersed electric switches for the purpose of separating oil from the 5 switch gases expelled from the switch during circuit interruption.

One of the objects of this invention is the provision of an oil separator of the general vortex type especially adapted for use in 10 connection with oil switches.

Another object of the invention is the provision of an oil separator of the vortex type with means to return the separated oil back to the switch through the inlet pipe to the 15 separating apparatus.

Another object of the invention is the provision of an oil separator of the vortex type having an entrance nozzle which is disposed in the upper part of the separator casing so 20 that the separated oil can circulate through the casing without passing across the nozzle.

A further object of the invention is generally to improve the construction and operation of separating devices.

25 Certain features of this invention are disclosed and claimed in my copending application Serial No. 216,877, filed September 1, 1927.

Fig. 1 is a side elevation partly in section 30 of an oil separating apparatus embodying this invention.

Fig. 2 is a plan view of the apparatus of Fig. 1 with the cover removed.

Fig. 3 is a sectional detail taken along line 35 3—3 of Fig. 1.

The separating apparatus embodying this invention comprises a cylindrical casing having the bottom wall 10 and the upstanding integral annular wall 12.

40 The casing is open at the top and is closed by a circular cover plate 14 which is attached removably to the casing over the top opening by means of bolts 16. The casing is provided with an upstanding central discharge tube 18 which is integral with the bottom wall and which has a discharge passage 20 therein down which the separated gases are adapted to flow and pass into a downwardly directed discharge pipe 22 which is screw threaded 45 into the lower open end of the tube 18. The

tube 18 is open at the top and is terminated above the top of the casing wall 12 and is located in a dome 24 formed in the cover plate 14. The side walls are spaced from said tube 18 to permit free communication between the tube and the interior of the casing. The side wall of the casing is provided with a vertically disposed projection 26 which is cored out to provide the vertical passage 28 therein. Said projection is terminated at its 55 lower end in a horizontal boss 30 into which the vent pipe 32 extended from the switch casing is screw threaded. The vertical passage 28 is in communication at its upper end with an aperture 34 in the side wall 12 of the casing and thence to the bowl 36 of a nozzle 38 which is disposed within the interior of the casing and at the top thereof. The mouth 40 of said nozzle is elongated in a vertical direction and the inclination of said 60 nozzle is such as to direct a stream of the mixture of oil and gas approximately tangentially against the inner face of the side wall so that the oil is caused to flow with a vortex motion about and in contact with the inner face of the side wall and gradually fall by gravity into the bottom of the casing. The gas, being lighter than the oil, passes to the interior of the casing and rises into the 65 dome 24 and flows downwardly through the tube 18 in the vent pipe 32 and escapes from the casing substantially free from any large amounts of oil.

The nozzle is in the upper part of the casing so that the oil as it revolves about the casing in contact with the side wall thereof will not flow over the nozzle.

85 The oil separated from the gas stream in the casing is adapted to be returned to the switch casing through the vent pipe 32. To 90 this end, an opening 42 is formed in the lower portion of the casing wall 12 in line with the vent pipe. A valve cage 44 is screw threaded in said opening and contains an outwardly opening valve 46 which is very lightly loaded to normally keep it closed. The valve is adapted to open after the pressure in the pipe 32 has subsided to allow the oil in the casing to flow out of the casing and return to the switch casing through the pipe 32. Said 95 100

pipe for this purpose is slightly inclined downward away from the casing.

I claim:

- 5 1. An oil separator comprising a circular casing having a gas outlet in the middle thereof and an entrance nozzle at the side thereof and an inlet pipe communicating with said nozzle, said casing having provision for returning the separated oil from said casing back through said inlet pipe.
- 10 2. An oil separator comprising a circular casing having a gas outlet in the middle thereof and an entrance nozzle at the side thereof directed to discharge fluid against the inner circular wall of the casing, and an inlet pipe communicating with said nozzle, said casing having provision for returning the separated oil from said casing back through said inlet pipe.
- 15 3. An oil separator comprising a cylindrical casing having an exit passage for the gas in the middle thereof and an entrance nozzle for the combined gas and liquid stream at the side thereof which is inclined to direct the stream against the cylindrical inner face of the casing, and an inlet pipe communicating with said nozzle, said casing having an opening in the lower portion thereof establishing communication between the interior of the casing and said inlet pipe and through which the separated oil can return into said inlet pipe.
- 20 4. An oil separator comprising a cylindrical casing having an exit passage for the gas in the middle thereof and an entrance nozzle for the combined gas and liquid stream at the side thereof which is inclined to direct the stream against the cylindrical inner face of the casing, and an inlet pipe communicating with said nozzle, said casing having an opening in the lower portion thereof establishing communication between the interior of the casing and said inlet pipe and through which the separated oil can return into said inlet pipe, and a check valve normally closing said opening against fluid flow therethrough into the casing.
- 25 5. An oil separator comprising a cylindrical casing having an inlet nozzle at the side directed to discharge the oil and gas stream at an inclination against the cylindrical inner face of the casing, an inlet passage communicating with said nozzle, a downwardly directed gas discharge tube disposed in the middle of the casing and having its upper end arranged in communication with the interior of the casing at the upper end of said casing, and a laterally extended oil discharge passage connecting the interior of said casing below said nozzle with said inlet passage.
- 30 6. An oil separator comprising an open top cylindrical casing having an entrance nozzle at one side arranged to discharge the liquid and gas stream against the cylindrical

inner face of the casing, an inlet pipe communicating with said nozzle, an upwardly extended discharge tube for the gases disposed in the middle of said casing and having its open upper end terminated above the top of the casing, a cover for said casing having a dome therein in which the open upper end of said tube is located, the side wall of said dome being spaced from said tube to establish communication between the interior of said casing and the open upper end of said tube, and a normally closed return passage for the separated oil connecting said inlet pipe and the bottom portion of said casing.

7. An oil separator comprising a cylindrical casing having an inlet passage, a discharge nozzle communicating with said passage disposed in the upper portion only of said casing at the side wall thereof and disposed and arranged to direct the liquid and gas stream onto the cylindrical inner face of said casing, a vertically extended discharge tube for the gas disposed in the middle of the casing and having an open upper end which is in communication with the interior of the casing at the top thereof, and a laterally disposed discharge passage for the oil communicating with the bottom portion of said casing and with said inlet passage.

8. An oil separator comprising a cylindrical casing having an outlet in the middle and an inlet nozzle located at the side wall and in the upper part of the casing and arranged to direct a liquid and gas stream onto the cylindrical inner face of the casing wall, said wall having an opening therethrough disposed beneath said nozzle, and an inlet pipe adapted for communication both with said opening and with said nozzle.

9. An oil separator comprising a cylindrical enclosing casing having a vertically extended discharge tube disposed in the middle of the casing and having an open top arranged in communication with the interior of said casing at the top thereof, a nozzle located in the upper portion of the casing at the side wall and arranged to direct the liquid and gas stream approximately tangentially onto the cylindrical inner face of said side wall, said side wall having an opening at the bottom thereof below said nozzle, and a horizontal inlet conduit arranged at the level of said opening and adapted for communication both with said opening and with said nozzle.

In testimony whereof, I have signed my name to this specification.

HENRY P. PINKHAM.
